UNITED STATES PATENT OFFICE

2,491,426

FLANGED CONTAINER CONSTRUCTION

William Tamoschat, New York, N. Y., assignor to
Daniel D. Zell, New York, N. Y.

Application July 3, 1946, Serial No. 681,341

4 Claims. (Cl. 220—31)

1

My invention relates to containers and more particularly to a container employing a flanged frame upon which is mounted an encircling frame member, and is an improvement on my Patent No. 2,218,665.

The principal object of my invention is to provide a container having flanged and encircling frame members, the outer frame member being interchangeable during the manufacturing process for accommodating changes in styles, materials and coverings without additional tool costs.

Other objects are to provide means whereby the encircling frame may be utilized to contain the latching mechanism for the container; to provide means for securing a flexible cover in position on the flanged frame, to provide means for providing a contrasting decorative scheme with the encircling frame member and for providing a multiplicity of differently appearing containers, all derived from a common basic structure.

I accomplish these and other objects and obtain my new results as will be apparent from the device described in the following specification, particularly pointed out in the claims, and illustrated in the accompanying drawing in which:

Fig. 1 is a top plan view of my container, illustrating one embodiment thereof;

Fig. 2 is a side elevation of the same;

Fig. 3 is an enlarged sectional view taken through 3—3 of Fig. 1;

Fig. 4 is an enlarged sectional view of a modification employing a flexible covering;

Fig. 5 is a similar view of a hinge-covering modification;

Fig. 6 is a similar view illustrating an encircling hollow U-shaped member.

Referring more in detail to the drawing, reference numeral 10 designates my container and comprises two complementary members 11 and 12 hinged at 13, and provided with a latching mechanism 14.

As illustrated in section in Fig. 3, section 11 comprises a tray-shaped member 15, having a top wall section 16, side walls 17 and a circumferentially extending flange 18.

The rear portion of the flange 18 is provided with hinges 13, as previously indicated.

An encircling frame member 19 is positioned about the tray-shaped member 15, fitting into the space provided by the side wall 17 and the flange 18. The inner wall 17 of the member 15 may be indented to provide notches 20, which fit into recesses 21 formed into the frame mem-

2

ber 19, and aligned therewith. The encircling frame-member may be slightly springy in assembly, to snap in position over the notches 20, to secure the frame member in position.

The latching mechanism comprises the finger piece 22 mounted on the flat spring 23 by means of rivet 24.

The front of the outer frame member 19 is hollowed out at 25 to provide a housing for the latch mechanism, the spring 23 resting on shoulder 26 and having a cut-out 27 to enable the finger piece 22 to extend therethrough, alongside the flange 18 and slightly beyond.

The top of the spring extends through apertures 28 and 29 in flange 18, and adjacent flange 18a, respectively, and is provided with a latch 30 for engaging the wall of flange 18a. Pressure applied to the finger piece compresses the spring 23, causing latch 30 to be moved clear of flange 18a, and allowing the two flanges to separate.

Latch 30 may be provided with a cam 31 to enable the latch to cam through opening 29 and lock when the two flanges are snapped together.

Space in the adjacent frame member 19a may be provided for the latch 30 by a recess 32.

It will be noted that the frame member 15 is provided with the inner wall 17 and flange 18 similarly to that shown in my former patent, No. 2,218,665. In fact, the same die for forming these parts may be employed. By providing the top wall 16 instead of using the flexible cover shown in my earlier patent, a tray-shaped structure is obtained, suitable for container use.

The parts described may be stamped from sheet metal into the desired form or may be molded from plastic material. Encircling frame member 19 too may also be made of metal, or of plastic material. One arrangement would be to make the tray-shaped member of metal, and the outer frame member of plastic.

Pleasing combinations may be employed, which are interchangeable with each other during production, and made up as desired or called for, without requiring additional tools or dies.

In Fig. 4, I have utilized the flanged frame member for securing a flexible cover to the tray-shaped member. The wall section 16 may be omitted entirely and flexible sheet material stretched across the opening. Thus in Fig. 4,

I illustrate two complementary members 40 and 41, hinged at 42, and each consisting of a frame member 43, having a side wall 44 and an extending flange 45. An inner liner sheet 46 may be stretched across the opening formed by the wall 44, and a flexible covering 47 of suitable material

stretched outside the liner, and downwardly between the outer surface of wall 44 and the inner surface of the encircling frame member 48, which may be snapped thereover, tightly compressing the marginal section 49 of the flexible covering therebetween.

Notches 50 may be similarly employed to secure the encircling frame member 48 to the side wall 44 by being slightly sprung over the recess 51. The marginal sections 49 of the outer cover may be thinned by chiving at the edges, allowing the notches to act more effectively and to assist in the clamping action of the outer frame member thereover. Instead of relying on the clamping action, the marginal sections of the cover may be glued or otherwise secured to the walls 44 to prevent loosening.

The encircling frame member may be shaped to provide any ornamental effect desired. It may be oval, rectangular or circularly shaped, and in cross-section, the external surface 52 may be suitably shaped as shown in Fig. 5, where a more streamlined effect is obtained. Here the encircling frame member 60 extends from the outer surface 61 of the flanged member 62 to the hinges 63, where the hollow portion 64 extends over the hinge to substantially hide it. The mouth 65 of the hollow portion permits the two complementary halves 66 and 67 to be opened to 90° or greater.

In Fig. 6, an encircling member 70 is shown which is U-shaped to reduce its weight. The hollow portion 71 may be filled with aluminum foil or other material which can be viewed through a transparent encircling member.

An elastic cigarette retaining member 72 may be provided by inserting the ends 73 through aperture 74 of wall 75 and applying to the end thereof, a retaining clip 76. When encircling member 70 is snapped over the indentation 77, a cut-out portion 78 enables the encircling member to accommodate clip 76 within the hollow portion 71.

I have thus described my invention, but I desire it understood that it is not confined to the particular forms or uses shown and described, the same being merely illustrative, and that the invention may be carried out in other ways without departing from the spirit of my invention, and, therefore, I claim broadly the right to employ all equivalent instrumentalities coming within the scope of the appended claims, and by means of which, objects of my invention are attained and new results accomplished, as it is obvious that the particular embodiments herein

shown and described are only some of the many that can be employed to attain these objects and accomplish these results.

What is claimed is:

5. A container of the class described, having an inner frame member provided with a continuous side wall and a laterally and outwardly extending flange; an externally positioned encircling frame member forming an open aperture within which aperture the continuous side wall of the inner frame member is seated; said encircling frame member having an outwardly extending contacting surface for engaging and covering the laterally extending flange of the inner frame member and a surface extending normally to said outwardly extending contacting surface; a top covering portion extending across the top of the continuous side wall and projecting through the aperture in the encircling frame member and visible therethrough; said inner frame member having its laterally extending flange provided with hinge and latching means; and securing means positioned on the side wall for securing the two members together.
10. 25. 2. The container of claim 1, wherein the top covering portion, the extending flange and the continuous wall are all made of a single piece of metal forming the inner frame member.
30. 3. The container of claim 1, wherein a retaining element is positioned from one side to the other of the continuous wall, the end portions of which extend through the wall and are covered by the encircling frame member.
35. 4. The container of claim 1, wherein the top covering portion is made of flexible material separate from the continuous wall of the inner frame member.

WILLIAM TAMOSCHAT.
